UNITED STATES PATENT OFFICE.

THOMAS M. WALKER, OF BELLEFONTAINE, OHIO, ASSIGNOR OF ONE-HALF
TO JOHN W. MILLER, OF SAME PLACE.

COMBINED POOL-RACK AND BALL-SPOTTER.

SPECIFICATION forming part of Letters Patent No. 323,835, dated August 4, 1885.

Application filed March 12, 1885. (No model.)

To all whom it may concern:

Be it known that I, THOMAS M. WALKER, of Bellefontaine, in the county of Logan and State of Ohio, have invented certain new and useful Improvements in Combined Pool-Rack, Ball-Spotter, and Game-Register; and I do hereby declare the following to be a full, clear, and exact description of the invention, such as will enable others skilled in the art to which it pertains to make and use it, reference being had to the accompanying drawings, which form part of this specification.

My invention relates to an improvement in an adjustable pool-rack, ball-spotter, and game-register combined; and it consists, first, in the combination of the triangle with ball-racks which are hinged to opposite sides, and gates for keeping the balls in the racks until it is desired to empty them into the triangle; second, the combination of a slotted support which is suspended from the ceiling over the table, the slide which moves in the slot, the triangle which is connected to the slide by means of rods, the ball-racks which are attached to the triangle, and the counter-weight for balancing the racks and triangle; third, the combination of the slotted support, the slide which moves in the support, the spring which is connected to the support, and which is operated by the slide, the dog which is attached to the lower end of the spring, and the notched slide which moves in the stationary register which is secured to the lower end of the slotted support, all of which will be more fully described hereinafter.

The object of my invention is to provide an apparatus which is to be suspended over pool-tables and in which the ball-racks are loosely connected to the triangle, so that the balls can be discharged at any time directly into the triangle, and which apparatus is adjustable up and down in relation to the table, and which automatically registers the number of games played.

Figure 1 is a side elevation of an apparatus embodying my invention complete. Fig. 2 is a similar view taken from the opposite side. Fig. 3 is a plan view of the racks and triangle alone. Fig. 4 is a vertical section of the slotted support, showing the spring for registering the games.

A represents a slotted support, which is rigidly secured to the ceiling at any suitable distance above the top of the pool-table, and which is slotted, as shown, so that the slide B can move vertically thereon. This support is suspended from the ceiling by means of the rod C, upon which the counter-weight D moves. This weight is connected to the slide B by means of suitable cords or chains, which are passed over the guide-pulleys E, secured to the ceiling. This weight should be just heavy enough to serve as a counter-balance for the triangle and ball-racks connected thereto.

The slide B consists of a suitable rectangular frame, which moves vertically upon the slotted support, and which has a triangle, F, rigidly secured to it by means of the rods G. This slide and the triangle are secured rigidly together, for the purpose of raising and lowering the triangle in relation to the table at any time. Hinged or otherwise loosely connected to opposite sides of the triangle are the two ball-racks H, which are supported at their outer ends by means of the chains I, which chains are connected at their inner and upper ends to the slide B. The slide, the triangle, and the racks, being thus secured together, are all raised and lowered at the same time, and are held in any desired position by means of the counter-weight.

In order to prevent the balls from dropping from the inner ends of the racks upon the table, or into the triangle above it, until it is desired to do so, each rack is provided with a spring-wire, L, which serves as a stop for the balls, and thus keeps them in position until it is desired to empty them into the rack.

As each player pockets a ball the ball is taken from the pocket and deposited in one of the partitions in the rack, and the ball then runs down to the inner and lower end of the rack, where it remains ready to be discharged into the triangle. When the game is completed, and it is desired to discharge the balls from the racks into the triangle, the cords or chains N, which are connected to the wires, are pulled up so as to raise the wires upward, and the balls drop into the triangle, which is held supported about three-fourths of an inch above the table. The racks are given just sufficient inclination to cause the balls to run readily

from the triangle whenever they are left free to do so.

Secured rigidly to the lower end of the slotted support A is the slotted register O, which 5 has a series of numbers marked upon it. Moving in this slotted register is a slide, P, which has its upper edge notched to correspond with the figures on the register, and with which notches the dog Q engages, for the purpose of pushing the slide forward each time the dog is operated. The end of the slide moves from figure to figure, and thus keeps tally of the number of games played.

Secured to the side of the slotted support 15 is the bent spring R, to the lower end of which the dog is loosely connected. Placed inside of the slotted support is a block, S, which is rigidly secured to the slide so as to move with it, and which block, each time that the slide, 20 triangle, and racks are lowered into position to place the balls for a new game, forces the lower end of the spring outward by striking against its lower curved end, and this spring forces the dog outward so as to move the slide another notch forward. When the triangle 25 and racks are raised above the table, the spring returns to position, and the dog is drawn back ready to operate the slide when the parts are again lowered.

30 Having thus described my invention, I claim—

1. The combination of the triangle with the

racks attached to opposite sides thereof and a suitable support for the racks and triangle, the support being adapted to be raised and 35 lowered, carrying the racks and triangle with it, substantially as shown.

2. The combination of the slotted support, the slide, and counter-weight with the triangle and the racks, which are secured to opposite 40 sides thereof, substantially as described.

3. The combination of a suitable support, the triangle, the two racks connected thereto, and the wires which act as stops to keep the balls in place in the racks, substantially as 45 set forth.

4. The combination of the slotted support, the slide and block, which move vertically thereon, the spring, the dog connected to the lower end of the spring, and the notched slide 50 placed in the register, substantially as specified.

5. The combination, in a single apparatus, of an automatic game - register, a triangle, the ball-racks connected thereto, and a counter-weight for holding these parts suspended in any desired position, substantially as shown.

In testimony whereof I affix my signature in presence of two witnesses.

THOMAS M. WALKER.
